UNITED STATES PATENT OFFICE.

HOWARD M. WEBSTER, OF CHICAGO, ILLINOIS.

PHOTOGRAPHIC-PRINTING APPARATUS.

1,262,723.

Specification of Letters Patent. Patented Apr. 16, 1918.

Application filed May 19, 1916. Serial No. 98,490.

To all whom it may concern:

Be it known that I, HOWARD M. WEBSTER, a citizen of the United States, residing at Chicago, in the county of Cook and State of Illinois, have invented certain new and useful Improvements in Photographic-Printing Apparatus, of which the following is a specification.

This invention relates to an apparatus for preparing photographic prints by artificial light and has for its principal object the provision of an apparatus of simple and relatively inexpensive construction, capable of rapid operation to produce photographic prints.

A further object of my invention is the provision in an apparatus of the above-described character of means for automatically shutting off the light after a predetermined interval.

Further objects and advantages of my invention will be apparent as it is better understood by reference to the following specification when read in connection with the accompanying drawing, illustrating the preferred embodiment thereof, in which—

Figure 1 is a plan view of an apparatus according to my invention;

Fig. 2 is a vertical section on the line 2—2 of Fig. 1;

Fig. 3 is a side elevation of the structure illustrated in Fig. 1;

Fig. 4 is a side elevation of a portion of the structure illustrating the printing position of the parts;

Fig. 5 is an enlarged detail in elevation of a portion of the time-controlling mechanism;

Fig. 6 is a vertical section through a portion of the printing mechanism;

Fig. 7 is a vertical section on the line 7—7 of Fig. 5; and

Fig. 8 is a vertical section on the line 8—8 of Fig. 5.

Referring to the drawings, 1 indicates a suitable casing, the upper end of which forms a table 2 adapted to support the printing mechanism. Within the casing 1 a plurality of electric lamps 3 and 4 are arranged, the lamps 3 being adapted to produce a white light and are intermittently operated while the lamp 4 is adapted to produce a red light and is operated constantly when the apparatus is in use.

On either side of the table 2 rods 5 are mounted in suitable brackets 6 and a carriage

7 is slidably mounted on the rods to move longitudinally of the table 2. A shaft 8, extending transversely of the table 2, is slidably mounted in slots 9 in the opposite sides of the carriage 7 and is resiliently drawn toward the table 2 by the springs 10. A roller 11 is mounted on the shaft 8 and connected thereto by a spiral spring 12 (Fig. 6) disposed within the roller 11. One edge of a blanket 13 is secured to the roller 11, the opposite end of the blanket being secured in any suitable manner to the surface of the table 2. A clamping member 14 is supported by links 16 which connect a shaft 17 mounted in brackets 18 on the clamping member 14 with a transverse member 15 of the carriage 7. A spring 19, connected to the shaft 17 and to a transverse member 20 of the carriage 7, normally raises the clamping member 14 from engagement with the surface of the table 2. Members 21 are supported on either side of the clamping member 14 and provided with laterally extending lugs 22. Upstanding members 23 secured to the table 2 are adapted to be engaged in the lugs 22 when the carriage 7 is moved to the right, viewing Fig. 3, to cause the clamping member 14 to approach the surface of the table 2.

In the operation of the mechanism the negative and the photographic paper are arranged over a glass inset 24 in the top of the table 2 and the carriage 7 is moved to the right, viewing Fig. 1, whereupon the blanket 13 is unrolled from the roller 11 above the negative and photographic paper and when the carriage 7 reaches the end of its movement, as indicated in Fig. 4, the clamping member 14 is operated, as previously stated, to clamp the work in position. A member 25 is arranged to slide transversely of the table 2 and is provided at its extremities with dogs 26 disposed in the path of the members 27 depending from the carriage 7. When the carriage reaches the position indicated in Fig. 4 the members 27 engage the dogs 26 to lock the carriage 7 in printing position. Springs 28, disposed about the rods 5, provide resilient buffers 105 to prevent injury of the carriage 7 by careless treatment.

To control the electric circuit leading to the lamps 3 I provide a member 29 adjustably mounted by means of screws 30 on the carriage 7 and having a laterally extending portion 31 adapted to engage a bell-crank

lever 32 pivoted at 32' on the side of the casing 1. A spring 33 normally maintains the bell-crank lever 32 in the position indicated in Fig. 3. A second bell-crank lever 34 is pivotally mounted concentrically with the bell-crank lever 32, one arm of the bell-crank lever 34 being disposed in the path of a pin 35 on the bell-crank lever 32. The other arm of the bell-crank lever 34 is connected to a contact member 36 slidably supported on a suitable insulating base 37 and provided with contacts 38 adapted to co-operate with contact members 39 resiliently mounted on the base 37. The contacts 38 and contact members 39 are connected by suitable conductors to a fuse box 40. A manually operable switch 41 controls the circuit in which the lamp 4 is arranged. A constant speed motor 42 is electrically connected by suitable conductors to a circuit controlled by a manually operable switch 43. The shaft 44 of the motor 42 is provided with a worm 45 engaging a suitable worm gear 46 arranged within a housing 47 and secured to a shaft 48 mounted in suitable bearing in the housing 47. The shaft 48 is provided at its end with a friction disk 49. Loosely mounted on the stub shaft 50, mounted in a bracket 51 secured to the side of the casing 2, is a spool 52 provided with friction springs 53 adapted to engage the friction disk 49. The bracket 51 is provided with a cam face 54 and a slotted member 55 provided with a corresponding cam face is mounted on the stub shaft 50 and connected by a link 56 to one end of the bell-crank lever 32.

Obviously when the bell-crank lever 32 is actuated in the manner previously described the member 55 will force the spool 52 to the left, viewing Fig. 5, to engage the friction disk 49 which is rotated at a constant speed by the motor 42. Connected to the spool 52 are a pair of flexible members 57 and 58 extending upwardly and over pulleys 59 and 60 mounted in the laterally extending brackets 61 and 62 secured to the side of the casing 1. The end of the flexible member 57 is connected to a weight 63 which normally rests on a support 64, the weight 63 being slidably disposed upon a vertical rod 65. An adjustable stop member 66 is mounted on the rod 65 in the path of the weight 63 which, as will be apparent from the preceding description, is lifted when the spool 52 is rotated. The rod 65 is slidable in the support 64 and is connected at its upper end to a lever 67 pivotally mounted in brackets 68 secured to the side of the table 2. An arm 69 of the lever 67 is disposed through a suitable opening in one of the dogs 26 so that when the rod 65 is lifted by engagement of the weight 63 with the adjustable stop 66 the dogs 26 are moved to release the members 27 so that the carriage 7 may be re-

turned to its normal position under the actuation of the springs 28 and 12.

The flexible member 58 is connected at its free end to a member 70 which is slidably mounted on the vertical rod 71 and a spring 72 is disposed about the rod 71 above the member 70. The purpose of the spring 72 and the member 70 is to resiliently stop the rotation of the spool 52 when the weight 63 returns to its normal position after the carriage 7 and the bell-crank lever 32 have been released.

The mode of operation of my invention will be readily understood from the following brief description thereof. The switches 41 and 43 being turned to position to operate the motor 42 and allow current to pass to the lamp 4, the negative and photographic paper are disposed upon the glass inset 24 and the carriage 7 is moved to the left, viewing Fig. 1, so that the blanket 13 is disposed above the photographic paper and the clamping member 14 is moved to the position indicated in Fig. 6. As the carriage 7 reaches the limit of its travel the contacts 38 are moved into engagement with the contact members 39 to close the circuit to the lamps 3. Simultaneously the springs 53 are moved into engagement with the friction disk 49 and the spool 52 commences to rotate and wind up the flexible member 57 to raise the weight 63. When the weight 63 engages the stop 66, which is previously adjusted in accordance with the time required to accomplish the printing operation, the rod 65 is moved vertically to operate the lever 67 and free the members 27 on the carriage 7 from the dogs 26, whereupon the carriage 7 returns to its normal position and the springs 53 are released from the friction disks 49, the spool 52 rotating in the reverse direction as the weight 63 descends. The printing paper is then removed and a fresh sheet substituted after which the operation is repeated.

It will be readily appreciated from the foregoing that I have perfected a photographic printing machine which is simple in construction, automatic in action and is adapted to produce photographic prints with extreme rapidity, the only attention necessary on the part of the operator being to replace the sheets of photographic printing paper and move the carriage 7 to printing position.

I am aware that various changes may be made in the form, construction and arrangement of the parts without departing from the spirit and scope of the invention or sacrificing any of its material advantages, the form hereinbefore described being merely a preferred embodiment thereof.

I claim:

1. In a photographic printing machine, the combination of a casing, electric lamps within said casing, a transparent top on

- 5 said casing above said lamps, a carriage
slidably movable to position above said
transparent top, means entirely supported
on said carriage and bodily movable rela-
tively thereto when the carriage is posi-
tioned above said transparent top to clamp
the work on said transparent top, means op-
erated by movement of said carriage for
closing the circuit to said lamps, and means
10 for automatically breaking said circuit after
a predetermined interval.
2. In a photographic printing machine,
the combination of a casing, electric lamps
within said casing, a transparent top on said
15 casing above said lamps, a carriage slidably
movable to position above said lamps, means
entirely supported on said carriage and
movable conjointly therewith and relatively
thereto to cover the work, means for retain-
20 ing said carriage in said position, and means
for releasing said carriage after a prede-
termined interval.
3. In a photographic printing machine,
the combination of a casing, electric lamps
25 within said casing, a transparent top on said
casing above said lamps, a carriage movable
to position above said transparent top, a
roller on said carriage, a blanket connected
to said roller and to the top of said casing,
30 means for rotating said roller to wind the
blanket thereon as said carriage moves in
one direction and to allow the blanket to
unroll as the carriage is moved in the oppo-
site direction, means entirely supported on
35 said carriage and bodily movable conjointly
therewith and relatively thereto to auto-
matically clamp the blanket and work on
said transparent top, means actuated by the
movement of said carriage to close a circuit
40 to said lamps, and means for automatically
breaking said circuit after a predetermined
interval.
4. In a photographic printing machine,
the combination of a casing, electric lamps
45 within said casing, a transparent top on
said casing above said lamps, a carriage
slidably movable to position above said
transparent top, a roller on said carriage, a
blanket connected to said roller and to the
50 top of said casing, means for rotating said
roller to wind the blanket thereon as said
carriage moves in one direction and to allow
the blanket to unroll as the carriage moves
in the opposite direction, and a clamping
55 member bodily movable conjointly with and
relatively to said carriage and adapted to
engage said blanket only when it is un-
rolled.
5. In a photographic printing machine,
60 the combination of a casing, electric lamps
within said casing, a transparent top on
said casing above said lamps, a carriage
movable to position about said transparent
top, means entirely supported on said car-
65 riage and bodily movable relatively thereto
when said carriage is positioned above said
transparent top to clamp the work on said
transparent top, a blanket, means on said
carriage for automatically positioning said
70 blanket between the work and clamping
means, means operated by the movement of
said carriage for closing a circuit to said
lamps, and means for automatically break-
ing said circuit after a predetermined in-
75 terval.
6. In a photographic printing machine,
the combination of a casing, electric lamps
within said casing, a transparent top on said
casing above said lamps, a carriage
movable to position above said transparent
80 top, a roller on said carriage, a blanket
connected to said roller and to the top of
said casing, means for rotating said roller
to wind the blanket thereon as said car-
riage moves in one direction and to allow
85 the blanket to unroll as the carriage moves
in the opposite direction, and means entirely
supported on said carriage and bodily mov-
able relatively thereto when said carriage
is positioned above said transparent top to
90 automatically clamp the blanket and work
on said transparent top.
7. In a photographic printing machine,
the combination of a casing, electric lamps
within said casing, a transparent top on said
casing above said lamps, a carriage movable
95 to position above said transparent top,
latches for maintaining said carriage in the
latter position, a roller on said carriage, a
blanket connected to said roller and to the
100 top of said casing, means for rotating said
roller to wind the blanket thereon as said
carriage moves in one direction and to al-
low the blanket to unroll as the carriage
moves in the opposite direction, means actu-
105 ated by the movement of said carriage for
closing a circuit to said lamps, and means
for automatically releasing said latches and
breaking said circuit after a predetermined
interval.
8. In a photographic printing machine,
the combination of a casing, electric lamps
110 within said casing, a transparent top on said
casing above said lamps, a carriage movable
to position above said lamps, means on said
carriage to cover the work, means for re-
taining said carriage in said position, means
115 automatically actuated when said carriage
is moved to said position to close a circuit
to said lamps, and means for automatically
releasing said carriage and breaking said
circuit after a predetermined interval.
9. In a photographic printing machine, the
combination of a casing, electric lamps with-
in said casing, a transparent top on said cas-
ing above said lamps, a carriage movable
120 to position above said lamps, spring-con-
trolled means on said carriage to cover the
work, means for retaining said carriage in
said position, means automatically actuated
125

when said carriage is moved to said position to close a circuit to said lamps, and means for automatically releasing said carriage and breaking said circuit after a predetermined interval.

10. In a photographic printing machine, the combination of a casing, electric lamps within said casing, a transparent top on said casing above said lamps, a carriage movable to printing position above said lamps, spring-controlled means on said carriage to cover the work, means on said carriage to clamp said spring-controlled means and the work, means for retaining said carriage in

printing position, means automatically actuated when said carriage is moved to printing position to close the circuit to said lamps and means for automatically releasing said carriage and breaking said circuit after a predetermined interval, including a continuously operable motor, mechanism connected to said retaining means and means for intermittently connecting said motor to said mechanism. 15
